UNITED STATES PATENT OFFICE.

MARSHALL S. CURTISS, OF PULLMAN, ILLINOIS.

RECLINING-CHAIR.

SPECIFICATION forming part of Letters Patent No. 280,356, dated July 3, 1883.

Application filed March 3, 1883. (No model.)

To all whom it may concern:

Be it known that I, MARSHALL S. CURTISS, a citizen of the United States, residing at Pullman, in the county of Cook and State of Illinois, have invented certain new and useful Improvements in Reclining-Chairs, of which the following is a specification.

This invention relates to reclining-chairs in which means are provided for tilting the back in order to allow the occupant to assume an inclined position.

The object of my invention is to dispense with the multiplicity of rods, bars, racks, and other appendages usually found in reclining-chairs, and to construct an exceedingly simple, durable, cheap, and serviceable reclining-chair for railroad, household, or other purposes, which, by a natural and easy movement of the body of its occupant either back or forward, can be operated so as to lower or raise the back at will and bring it into any desired inclined position, in which condition it will be balanced and retained by either the distributed weight of the occupant when at rest or by the distribution of the weight of its own members when not occupied. These objects I attain by the construction of chair hereinafter fully described, and illustrated in the annexed drawings, in which—

Figure 1 represents in perspective a reclining-chair constructed in accordance with my invention. Fig. 2 is a longitudinal vertical section with the back lowered or tilted rearwardly. Fig. 3 is a like view with a somewhat modified arrangement of swinging supports for the arm-rests.

Referring by letter to the annexed drawings, A indicates the tilting-chair back, which is supported upon a base, B, to which it is pivoted or hinged, the connection herein shown between the back and base being made by means of ordinary hinges. The back is also hinged to or flexibly connected with the seat C, whereby the back is capable of being tilted backward from its usual upright position to such angle as may be preferred by an occupant of the chair desiring to assume an inclined or recumbent attitude. The seat is constructed independently of the base B, and is supported by or suspended from the same in such manner that when pressure is exerted laterally

against the back, so as to tilt it down rearwardly, a simultaneous upward movement will be given to the seat, and conversely, when sufficient pressure is exerted downwardly upon the seat, so as to lower it and overcome the weight of and resistance against the back, the latter will be raised to or toward its upright or normal position.

The arm-rests D are pivoted at their rear ends to the chair-back, and at their front ends are upheld by means of swinging supports E, which take the place of the ordinary stationary front posts of a chair. These swinging supports are hinged or pivoted to the arm-rests, and are free to vibrate about their lower fulcrum points, so as to allow the arm-rests to move simultaneously with the back.

When the chair-back is tilted down into an inclined position, the arm-rests will be drawn downwardly and backwardly, and when the back is raised the arm-rests will have a simultaneous upward and forward movement. When the back is tilted down to an inclined position, its lower end will be raised to a degree depending upon the distance to which said end extends below the point of support for the back. The rear end of the seat, which is flexibly connected with the lower end of the back, will consequently be raised or lowered according to the direction in which the back is tilted. In order, therefore, to also raise or lower the front end of the seat so as to cause both ends of the seat to move alike, and thereby maintain the seat at all times in a substantially horizontal position, I construct the supports for the arm-rests in the nature of bent levers, each having a long arm, e, which is pivoted to one of the arm-rests, and a short arm, e', which is pivotally connected with the seat at or near the front of the latter.

In Figs. 1 and 2 these bent arms or levers, which constitute link-connections between the arm-rests and the base, are pivoted at their bends to the base B, and have their short arms, which are connected with the seat, extended forward; but the same result can be attained by pivoting the bent levers at their bends to the seat and extending their short arms rearwardly and pivoting the same to the base, as illustrated in Fig. 3. This last arrangement may in some cases be preferable, since the short

arms of the levers can thereby be interposed between the sides of the seat and the base, although by setting the levers farther back or extending the base forward the same result will be practically attained. In either instance, however, when the chair-back is tilted rearwardly, the levers will be vibrated by reason of their connection with the arm-rests, and hence the forward part of the chair-seat will be raised correspondingly with the upward movement of its rear end, and when the seat is depressed the back will be raised both by reason of its direct connection with the seat and through the medium of the arm-rests and bent levers which constitute jointed connections between the seat and the back.

The back and seat frames can be covered with one or separate pieces of cloth, leather, or other material suitable for the purpose, and can be upholstered in any desired manner.

In constructing a reclining-chair in accordance with my invention it will be evident that the back-frame can be made of the usual rectangular or other preferred shape and hinged or pivoted directly to the base, and that various modes of hinging or pivotally connecting the said members can be employed.

In the chair illustrated in the drawings I have constructed the back with a substantially rectangular frame having auxiliary side bars, F, which are rigidly secured at the top to the side bars, a, of the main frame, and at their lower ends hinged to the base. The arm-rests are in this instance hinged or pivoted to the bars a, and the bars a and F are arranged so as to diverge at their lower ends, in order to throw the lower portion of the upholstered or covered part of the back-frame forward. These side bars, a, also extend somewhat below the points of support of the outer hinged bars, F, so that the connection between the back and the seat can be made below the axis about which the back turns, and thereby sufficient leverage obtained when the seat is depressed so as to raise the back.

The base B can be constructed either as shown or in any convenient or suitable way, the form and disposition of the legs or supports and rounds being essentially a matter of taste with the manufacturer.

The swinging supports for the arm-rests can

be made of metal and incased by a covering of wood or other material; or they can be made of metal alone and polished, nickel-plated, or otherwise treated, as preferred.

A chair constructed as hereinbefore described can be readily converted at the will of the occupant from an upright-back into a reclining-back chair, or the reverse, as desired.

By leaning against and pressing backward upon the chair-back, so as to throw to some extent the weight of the body to the rear, the back can be inclined, and by slightly throwing the weight forward upon the seat the back can be raised, since the seat and back are so balanced and the weight of the occupant so distributed that but little exertion will be necessary to raise the back from an inclined to an upright position.

Having thus described my invention, what I claim, and desire to secure by Letters Patent, is—

1. The combination of a supporting-base, a back-frame hinged thereto, a back separate from said back-frame, but connected to the upper part of the same, a seat flexibly connected with said back, and devices, substantially as described, connecting the seat with the supporting base and back, substantially as and for the purpose set forth.

2. The combination, with the supporting-base and a back-frame hinged thereto, of a back separate from the back-frame, but connected with the upper part of the same, a seat flexibly connected to the back, the arm-rests, and the bell-crank levers connecting said arm-rests with the base and seat, substantially as described.

3. The combination, in a reclining-chair, of a supporting-base, a back-frame hinged to the base, a back separate from the back-frame, but connected to the upper part of the same, a seat and arms flexibly connected to said back, and swinging bent levers pivoted centrally to the base, one end being pivoted to the arm-rests and the other end to the seat, substantially as described.

MARSHALL S. CURTISS.
